CLAIM

The ornamental design for a hat rack as shown and described.

DESCRIPTION

FIG. 1 is a perspective view of the hat rack showing my new design;

FIG. 2 is a front view thereof;

FIG. 3 is a rear view thereof;

FIG. 4 is a right view thereof;

FIG. 5 is a left view thereof;

FIG. 6 is a top view thereof;

FIG. 7 is a bottom view thereof;

FIG. 8 is another perspective view thereof; and,

FIG. 9 is an exploded perspective view thereof.

The broken lines shown represent portions of the hat rack that form no part of the claimed design.
